UNITED STATES PATENT OFFICE

90,696

DESIGN FOR A BASSINET

Howard B. Caldwell, Morrison, Va.

Application June 7, 1933. Serial No. 48,304

Term of patent 3½ years

To all whom it may concern:

Be it known that I, HOWARD B. CALDWELL, a citizen of the United States, residing at Morrison, in the county of Warwick and State of Virginia, have invented a new, original, and ornamental Design for a Bassinet, of which the following is a specification, reference being had to the accompanying drawing, forming part thereof.

The single figure is a perspective view of a bassinet, showing my new design.

I claim:—

The ornamental design for a bassinet as shown.

HOWARD B. CALDWELL.
